UNITED STATES PATENT OFFICE.

ROLLA O. HEIKES, OF DAYTON, OHIO.

TRY-OUT PAD FOR GUN-STOCKS AND OTHER ARTICLES.

1,258,771.

Specification of Letters Patent. Patented Mar. 12, 1918.

Application filed April 13, 1917. Serial No. 161,865.

To all whom it may concern:

Be it known that I, ROLLA O. HEIKES, citizen of the United States, residing at Dayton, in the county of Montgomery and State 5 of Ohio, have invented certain new and useful Improvements in Try-Out Pads for Gun-Stocks and other Articles, of which the following is a specification.

My invention relates to fire arms and more 10 particularly to a "try-out" pad for gun stocks.

It is quite essential that marksmen shall have a gun stock properly fitted and shaped to his physical peculiarities and deviations 15 in order to attain best results. A man whose neck is abnormally short will require a different degree of "drop" in the stock from one who is provided by nature with an unusually long neck. Likewise a broad shoul- 20 dered man and one of narrow shoulders will not use to the best advantage a stock of the same proportion. The contour of the face or cheek and the height of the cheek bone also are controlling factors in the develop- 25 ment of a properly proportioned gun stock. Marksmen generally and particularly persons so engaged professionally are extremely critical and observant of such niceties of proportion. To meet such requirements a 30 gun stock may require a greater or less degree of drop that is angular inclination to the lineal direction of the barrel. It may necessitate a stock of greater or less height measured perpendicular to the direction of 35 the barrels or perpendicular to the general line of "drop" independent of the degree of such drop. Such stock may also involve variations of thickness either over the entire stock or perhaps only at certain localized 40 points.

These variations of proportion to meet the requirement of different marksmen are subservient to no particular rule or to mathematical development, but may be determined only by repeated tests and experiment. To develop the proper proportions and shape involves repeated trials and necessitates both adding to and deducting from different portions of the stock. To make such 50 changes in an actual wood stock involves considerable expense and difficulty as well as requiring considerable time; such changes cannot ordinarily be made quickly at the proving ground.

One of the primary objects of the present 55 invention is to enable the contour of the stock to be readily and quickly varied by the marksman himself without the aid of skilled mechanics, and at the moment of actual tests either by adding to or deducting from the bulk of the stock at such points as may be thought desirable. It may be necessary to make such changes repeatedly and in different locations before the proper 60 contour is finally developed. One of the objects is to enable the marksman to develop a pattern stock accurately suited and fitted to his particular needs from which a permanent stock may be subsequently made by the 65 skilled mechanic.

Further objects of the invention is to sim- 70 plify the development of special stocks as well as the means and mode of operation whereby they will not only be cheapened in construction, but may be more rapidly and 75 accurately proportioned, capable of being employed by persons unskilled in variable shape turning or gun stock manufacture and whereby the same material may be re-used to develop a different contour for a different 80 gun or marksman.

With the above primary and other inci- 85 dental objects in view as will more fully appear in the specification, the invention consists of the features of construction, the parts and combinations thereof, and the process or method of operation or their equivalents, as hereinafter described and set forth in the claims.

Referring to the drawings Figure 1 is a 90 perspective view of a gun stock to which the variable try-out pad construction forming the subject matter hereof has been applied. Fig. 2 is a transverse sectional view of the stock and scabbard with the inserted 95 pads or filling material variously disposed.

Like parts are indicated by similar characters of reference throughout the several views.

Referring to the drawings 1 is a gun 100 stock of standard proportions or if so desired it may comprise a "dummy" or foundation body of approximately the shape of the standard stock. Inclosing this stock or foundation form is a sleeve or scabbard 2 of 105 elastic material preferably rubber, opened at its opposite ends, through which the gun may be introduced barrel foremost. This

sleeve or scabbard 2 is shaped to the approximate proportions and general shape of the usual gun stock. It is preferably though not necessarily provided with an extension 5 or neck 3 of less diameter than the main body of the scabbard, conforming to the grip portion of the stock. This neck or extension 3 may be of any desired length or may be omitted entirely if the proportioning 10 of the grip of the stock is not required. Being constructed of elastic material the scabbard or sleeve 2 contracts into close conformity with the foundation body or stock 1.

Having assembled the scabbard upon the 15 stock the marksman determines at which points he believes the stock should be built up to suit his particular needs. He then proceeds to insert pad material over the selected locations intermediate the stock body 20 1 and the scabbard 2. Such pad material may be of any suitable nature such as fabric, lint, waste or similar material but is preferably splints or sheets of wood or cardboard or even thin sheets of paper may be 25 employed for finer degrees of adjustment. These inserts may be overlaid one upon the other in different locations. For instance a plurality of the inserts or pads bent to proper shape may be saddled upon the upper 30 edge of the stock beneath the scabbard 2 as indicated at 4, to raise the drop of the stock. These inserts may not necessarily extend the entire length of the stock. It may be necessary to insert separate pads or fillers, for instance at the point 5 farther forward upon the stock. Other pads or inserts 35 may be inserted as at 6 to extend the cheek of the stock. It may be noted that some shooters for personal reasons may prefer 40 one side or cheek of the stock to be convex to a greater degree than the other. To determine the degree and location of such fullness additional inserts or pads will be interposed between the stock and the scabbard 45 upon that particular spot. Likewise the size and shape of the grip portion of the stock may be varied by inserting or removing other inserts or pads 7.

Having distributed the pads or inserts as 50 experience or fancy may seem to dictate, the marksman tests the padded stock in actual use. If he finds his first estimate of proportions incorrect, he may add to or deduct from the insert or padding, or he may shift 55 the location of the pads increasing them in one locality and decreasing them in another until he ascertains the true or desired shape of stock to meet his particular requirements.

60 The proportions and contour of the stock having been developed to his satisfaction the padded form is then employed as a pattern or master stock from which to fashion the required stock of like shape wholly in 65 wood.

I am well aware that cushioned boots or scabbards have heretofore been employed on gun stocks for protecting the marksman against recoil. In some instances boots of leather have been provided to be laced or 70 tied upon the stock and to inclose pneumatic or other cushion to protect the face of the marksman against recoil, and also that rigid splints have been permanently attached to gun stocks to change the dimension thereof. 75 These devices however are for permanent use upon a particular stock and are not to be confused with the present invention which is for a different purpose, viz, that of developing, and enabling the marksman to 80 tryout, different shapes of stock which are to be subsequently embodied in permanent form.

While the invention is particularly applicable to the development of gun stocks 85 and has been so described it is to be understood that it may also be applied to the development of other variably shaped patterns or devices to be subsequently embodied in permanent form. I therefore do not wish 90 to limit the process to the development of gun stocks alone.

From the above description it will be apparent that there is thus provided a device of the character described, possessing 95 the particular features of advantage before enumerated as desirable but which is susceptible of modification in its form, proportion, detail construction or arrangement of parts, without departing from the principle 100 involved or sacrificing any of its advantages.

While in order to comply with the statute the invention has been described in language more or less specific as to certain structural features, it is to be understood that the invention is not limited to any specific details, but that the means and construction herein described comprise but one mode of putting the invention into effect, and the invention is therefore claimed broadly in any 105 of its possible forms or modifications within the scope of the appended claims.

Having thus described my invention I claim:—

1. The herein described method of developing the proportions and contour of a gun stock or other article, comprising inclosing a foundation body or core in an elastic sheath or scabbard, and then inserting movable distension pads or inserts intermediate the core 115 or foundation body and the elastic sheath or scabbard to distend the latter to the desired contour, and subsequently employing the contoured form thus produced as a master pattern in fashioning the permanent gun 120 stock or other article.

2. The herein described method of developing the proportions and contour of gun stocks or other irregularly shaped articles, comprising inclosing a substantially rigid 125

core in an elastic inclosure, distending the elastic inclosure unequally at different points, and subsequently employing the distended inclosure as a master pattern for the fashioning of the article in permanent form.

5. In a device of the character described, an elastic scabbard or sleeve open at both its ends through which a gun or like article may be introduced barrel foremost, said 10 elastic scabbard or sleeve being normally of less peripheral size than the stock of the gun or other article inserted therein whereby said scabbard or sleeve will cling to the inserted body, and independent movable inserts introduced within the elastic sleeve or scabbard and held in adjusted position by 15 the clamping action of the sleeve or scabbard.
4. The combination with a gun stock, of 20 an elastic sleeve or scabbard open at its opposite ends inclosing said stock through which the gun is introduced barrel foremost, and means for distending said elastic scab-

bard or sleeve to change the external contour of the body.

5. The combination with a gun stock, of 25 an elastic scabbard or sleeve inclosing the gun stock, and one or more independent, movable inserts introduced intermediate the stock and the elastic sleeve to change the external contour of the latter, substantially as specified.

6. The combination with a gun stock, of 30 an elastic scabbard or sleeve inclosing the gun stock, said scabbard or sleeve having a 35 hose-like extension adapted to inclose the grip of the stock, and means for locally expanding said scabbard or sleeve substantially as specified.

In testimony whereof, I have hereunto set 40 my hand this 5 day of April, A. D. 1917.

ROLLA O. HEIKES.
